FOLDING BAYONET FOR FIREARMS

George William Patchett, Chigwell, England

Application June 16, 1944, Serial No. 540,693
In Great Britain March 13, 1944

5 Claims. (Cl. 42—86)

1

This invention relates to a new or improved folding bayonet for firearms.

The object of the invention is to provide an additional weapon of a hook-on defence that normally can lie parallel to the longitudinal axis of the firearm in its folded or inoperative condition, but when occasion demands or at close quarters, can be instantly released, the bayonet thereafter snapping itself under resilient urge into a forward and locked condition for operative use.

While the said folding bayonet, the subject of the present invention, is applicable to every type of rifle, carbine or like weapon, it is more particularly useful when applied to firearms of the automatic class, and the description set forth hereinafter shows the said bayonet so applied.

Preferably the bayonet can have a length that is approximately that between the muzzle of the firearm and a point adjacent the trigger guard, the said bayonet being hinged about the barrel muzzle and folding below the barrel, barrel casing and forward stock, if any.

The invention consists in a folding bayonet for firearms having in combination a clip, collar or like support about the muzzle of the said firearm, a bayonet hinged within said clip, a spring loaded plunger housed in the substance of shoulder of said bayonet adjacent said hinge, a recess in said muzzle collar or clip to receive and hold said plunger, a resilient device loadable on folding to impel said bayonet to an operatively fixed condition in release, and resilient catch means to lock said bayonet in a folded condition and instantly release same therefrom at will.

The said bayonet is devised to lie parallel with the longitudinal axis of the firearm when in the folded condition and the resilient means giving the urge to the bayonet taking and following an arcuate path to fixity in an operative condition is placed adjacent the bayonet hinge.

The point of the bayonet is adapted to snap into a resiliently displaceable catch, said catch being under control of a spring-loaded thumb press lever, a finger guard intervening between the bayonet blade point and the thumb release.

In order that the invention may be more fully described, reference is made to the accompanying drawings wherein a preferred embodiment of the invention is illustrated and wherein:

Fig. 1 is a curtailed longitudinal elevation of a firearm of the automatic type, and the bayonet in its folded condition.

Fig. 2 is a side elevation, partly in section, of

2

the muzzle part of the firearm with the bayonet in its locked operative condition.

Fig. 3 is an end view of Fig. 1 facing the muzzle of the firearm.

Fig. 4 is a transverse section taken on the line 4—4 in Fig. 1.

Fig. 5 is a detail sectional view on an enlarged scale of the resilient bayonet pusher and its housing.

Fig. 6 is a transverse section taken on the line 6—6 in Fig. 1.

Fig. 7 is a transverse section taken on the line 7—7 in Fig. 1.

Fig. 8 is an elevation of the bayonet catch and control connection with thumb lever.

Fig. 9 is a cross section taken on line 9—9 of Fig. 8.

Referring to the drawings and to Figs. 1, 2 and 3, the firearm barrel 1 is provided with a muzzle nose ring 2 perforated as at 3, one of which said perforations 3a constitutes the locking socket. The nose ring 2 constitutes the forward support for the casing 4, and over this casing is disposed a collar or clip 5 fast therewith.

Said collar 5 is formed with lugs 6 adapted to receive the tang 7 of the bayonet blade 8. A pivot pin 9 passes through the lugs 6 and tang 7 and upon said pin the bayonet 8 freely hinges. Set in the shoulder of the bayonet 8 is a spring-loaded plunger 11, said plunger normally protruding as shown in Fig. 1, but capable of manual withdrawal by means of the knurled knob 12 against action of a spring 13. A resilient spring-loaded pusher or impelling device 14 is mounted

within a cylinder 15, secured between the external face of the firearm casing 4, and barrel 1 (see Fig. 2). Said cylinder 15 is closed by a threaded cap 16. Springs 17 urge the pusher or impeller to occupy a limit of travel position as shown in Fig. 5. Said pusher 14 is located adjacent the hinge 9 to bear upon the back of the bayonet blade or shoulder 10. The bayonet blade adjacent its point is adapted to engage a resilient catch 20 (see Figs. 6, 7 and 8). Said catch 20 is capable of angular movement about its pivot spindle 21 in a plane at right angles to the blade movement upon its pivot 9. The catch 20 is fixed to the spindle or arbor 21, the latter being journaled in a bearing 22 fast in protector plate or shield 23. At the rear of the protector plate or shield 23 and fast with the spindle 21 is a thumb press lever 24, said lever being urged away from the trigger housing 25 by a leaf or like spring 26. To enable the catch 20 to have a limited angular movement, the end of its boss 27 adja-

1

cent to the bearing 22 is of segmental form and the adjacent end of the bearing 22 is also of segmental form, these segmental portions meshing but forming less than a complete circle, thus giving an angular range of motion to said catch according to the arc of the peripheral gap 28 thus formed between these segmental portions and providing limit stops for such angular motion. This is shown in Fig. 9 wherein a side elevation of the catch is illustrated looking in the direction indicated by the arrows on line D—D, Fig. 8.

The operation of the invention is as follows: Assuming the bayonet to be folded and in its inoperative condition, as shown in Fig. 1, the resilient pusher or impeller 14 is loaded and presses heavily upon the bayonet shoulder 10; the bayonet is caught about its point in the catch 20, the latter being resiliently restrained from movement by the leaf spring 26. To instantly release the bayonet 8 the gunner presses the thumb lever 24 which is conveniently adjacent the trigger 18; this flexes the spring 26 causing the spindle 21 to rotate, and thus cause the catch 20 to move away from the bayonet 8 and release it. The bayonet is now free and has arcuate movement about the pivot pin 9 under the influence of the spring loaded pusher 14. The bayonet gains sufficient momentum to swing 180°, the spring loaded plunger 11 engaging and collapsing against the face of the nose ring 3 until said plunger in its path enters the locking socket 3a down which it travels maintaining thereby the said bayonet in an operative position aligned with the rifle or firearm. This action is substantially instantaneous, but can even be expedited by giving the firearm an upward jerk when the bayonet has once started on its arcuate swing. To release and fold the bayonet, the plunger pin 12 is pulled, withdrawing the plunger 11. The bayonet 8 is now free to hinge and by passing the hand down the back of the blade of the bayonet its point engages the catch 20 as previously described.

I claim:

1. In a firearm, a barrel, a spaced casing surrounding said barrel, a nose ring connecting said barrel and casing at the muzzle end, a clip at the muzzle end of the firearm, a releasable catch, and an impelling device comprising a cylinder mounted between said barrel and casing, a pusher reciprocable in said cylinder, a spring urging said pusher outwardly in a direction transversely of said barrel, a bayonet pivoted to said clip to swing rearwardly into folded position longitudinally of the barrel and to load the pusher actuating spring of said impelling device and engage said catch to hold the bayonet in folded position against the loaded action of said impelling device, and to swing forwardly into an extended position longitudinally of the barrel, and means for locking the bayonet in said forwardly extended position, said impelling device being operative on the bayonet to swing it forwardly into said extended position longitudinally of the barrel and into engagement with said locking means when said catch is released.

2. The combination according to claim 1, wherein said nose ring is provided with a plurality of perforations, and including a spring-loaded

5 plunger mounted on the bayonet adjacent to its pivot to move longitudinally of the bayonet and engageable in one of said perforations in the nose ring when the bayonet is swung about its pivot into extended position to lock the bayonet in said position.

3. The combination of a firearm having a barrel and barrel casing, and a clip, a releasable catch and a resilient impelling device mounted on said casing, said impelling device acting in a direction transversely of the barrel, a bayonet pivoted to said clip to swing rearwardly into folded position longitudinally of the barrel and to load said impelling device and engage said catch to hold the bayonet in folded position against the loaded action of said impelling device, a protector plate fixed to and projecting laterally from the side of said firearm, a spindle journaled in said plate, said releasable catch being fixed to said spindle at the forward side of said plate, and a manually operable releasing lever fixed on said spindle at the rear side of said plate whereby said catch is rotatable by said spindle to release the bayonet by the operation of said lever.

4. The combination of a firearm having a barrel and barrel casing, and a clip, a releasable catch and a resilient impelling device mounted on said barrel casing, said impelling device acting in a direction transversely of the barrel, a bayonet pivoted to said clip to swing rearwardly into folded position longitudinally of the barrel and to load said impelling device and engage said catch to hold the bayonet in folded position against the loaded action of said impelling device, a bearing fixed to the side of said firearm, a spindle journaled in said bearing, said catch being fixed to the forward end of said spindle to rotate therewith, a lever fixed on the rear end of said spindle, a spring acting on said lever to hold said catch in engagement with the bayonet when folded, and said lever being operable to manually rotate said spindle to release the catch.

5. The combination defined in claim 4, wherein the adjacent portions of said catch and bearing are of segmental form and are in meshing relation to provide stops to limit the rotation of the catch under the action of the spring.

GEORGE WILLIAM PATCHETT.
